US0D1035231S

(12) **United States Design Patent** (10) **Patent No.:** **US D1,035,231 S**
(45) **Date of Patent:** **** Jul. 16, 2024**

(54) **SHOE**(71) Applicant: **adidas AG**, Herzogenaurach (DE)(72) Inventor: **Moritz Hoellmueller**, Herzogenaurach (DE)(73) Assignee: **adidas AG**, Herzogenaurach (DE)(***) Term: **15 Years**(21) Appl. No.: **29/760,713**(22) Filed: **Dec. 3, 2020****Related U.S. Application Data**

(63) Continuation of application No. 29/664,097, filed on Sep. 21, 2018, now Pat. No. Des. 906,648, which is a continuation of application No. 29/591,016, filed on Jan. 16, 2017, now Pat. No. Des. 828,991, which is a continuation of application No. 29/550,418, filed on Jan. 4, 2016, now Pat. No. Des. 776,410, which is a continuation of application No. 29/464,051, filed on Aug. 12, 2013, now Pat. No. Des. 758,056.

(57) CLAIM

The ornamental design for a shoe, as shown and described.

DESCRIPTION

FIG. 1 is a side view of a shoe; and, FIG. 2 is an enlarged view of the portion labeled 2 in the FIG. 1 view.

In the drawings, the dash-dot-dash lines are unclaimed boundaries that surround the claimed portion of the shoe. Everything outside of the dash-dot-dash boundaries is unclaimed and forms no part of the claimed design. The dash-dot-dash lines are for purposes of illustrating the edges of the shoe and also form no part of the claimed design. The dash-dot-dot-dash lines show the area of enlargement in the FIG. 1 and FIG. 2 views and form no part of the claimed design.
